UNITED STATES PATENT OFFICE.

FREDERICK GEORGE GARRETT, OF SOUTHALL, ENGLAND.

DOOR HINGE.

Application filed June 14, 1926, Serial No. 115,706, and in Great Britain July 27, 1925.

This invention relates to door hinges of the kind which when the door is closed are concealed between the door and the door-post or body structure, so that in addition to the usual swinging movements of the door it is necessary to provide for a transverse or pivotal outward movement of the door hinge plate or part of the hinge secured to the door in opening it, and conversely for a reverse or inward movement of the said part in closing the door. These outward and inward movements of the door hinge plate have previously been obtained by means of parallel arms or links pivoted on the body hinge plate co-operating with a spur on the door hinge plate, which spur in one construction worked against a cam surface on one of the said arms in the outward or opening movement only.

According to the present invention a cross link connects the spur with an intermediate part of the pivoted arm remote from the spur, in order to hold the spur in contact with the cam surface on the arm adjacent to the spur so as to ensure positive action of the spur in both the opening and closing movements, and also in order to obtain a half-lock action, that is to say, to check slamming or violent opening and closing movements of the door by providing for a slight stiffness in the working of the hinge at one point in the opening or closing movement. The link may pass through an aperture in the arm comprising the cam surface.

The body hinge plate may be attached in a readily removable manner to a lining or casing permanently secured in the post or body, the attachment being made by set screws, for example, this lining or casing overlapping the said hinge plate at both its top and bottom edges.

Hinges of the kind to which this invention relates are especially applicable for use on the doors of motor and other vehicles, but I wish it to be understood that references to "doors" in this specification are also intended to include similar hinged closing members for which a concealed hinge of this kind is suitable, for example, safe doors, French windows, ships' portholes, skylights, piano lids, cash-box lids and hinged closing members used for various purposes in engineering wherein ordinary hinges might be obstructive or otherwise inefficient or be detrimentally affected by direct ex-

posure to heat or to corrosive liquids or gases.

In order that the said invention may be clearly understood and readily carried into effect, the same will now be described more fully with reference to the accompanying drawings, wherein:—

Figure 1 is an elevation taken in the direction of the arrow I in Figure 3 representing a hinge embodying this invention in the open position.

Figure 2 is an elevation taken in the direction of the arrow II in Figure 4 representing the said hinge in its closed position.

Figure 3 is a plan of the hinge open.

Figure 4 is a plan of the hinge closed.

Figures 5 to 11 illustrate constructional details detached, Figures 5, 6 and 7 being elevations of the door plate and the permanent and detachable body plates respectively, while Figures 8, 9, 10 and 11 are plans of the inner arm, outer arm, spur-link, and a connecting arm respectively.

A indicates a lining, casing, socket, or channelled plate, hereinafter called the permanent body plate, which is intended to be fitted into a recess in the door post or body pillar of a vehicle, for example, with its flanges a' , a'' (see Figure 6) facing outwardly, that is, towards the door, the plate being secured by four long and strong screws passing through the countersunk holes a^3 in these flanges, and the said flanges being then if desired filled, painted and varnished over to match the remainder of the carriage body. In the front of the permanent body plate A are threaded holes a^4 , a^5 for the reception of grub screws by which the detachable body hinge plate B can be secured in the said permanent body plate. Projecting from the permanent body plate A are pins a^6 (Figures 2 and 6) adapted to register in notches b' (Figure 7) in the detachable body hinge plate, so that in the event of the door being wrenched back, as in an accident, the said grub screws would break away in preference to those screws securing the permanent body plate to the door post or body, the screws in the holes a^4 giving way first, allowing the detachable body hinge plate B to tilt or pivot on the pins a^6 , thus tending to prevent any serious damage to the body of the vehicle (not shown).

In the channel or recess of the plate B are

pivottally secured parallel arms C, D to the outer ends of which are pivoted connecting arms E, E', these latter arms being in turn pivottally connected with the door plate F. 5 This door plate is provided with countersunk holes f' through which can pass screws for connecting it with the door (not shown), and from the inner part of the said plate F projects a spur G adapted to work in contact with the rounded outer face d' of the arm D (see Figures 3 and 9). This spur G is bifurcated as seen in Figures 2 and 5 to form jaws g', g² in which is pivottally secured one end of a link H (best seen in Figures 3 and 10), which link passes through a slot in the arm D and its other end is pivottally connected with the arm C (see Figure 3). 10 In order to effect the desired action in both the opening and closing movements, it is essential that the bifurcated extremity of the spur G should move upon, and be held in constant contact with the cam surface d' of the arm D, and this positive action is ensured by the spur G being pivottally connected with the link H, which in turn is pivottally secured to the arm C at such a point on the said arm C as will ensure the pivot of the link H remote from the arm C 15 moving in an arc to conform exactly with that of the cam surface. This balance and arrangement causes the spur G, link H, arm D, and cam surface d' to work in perfect unison. The positive action of the spur G 20 upon the cam surface d' through the interaction of the link H and the arms E, E', also causes the arm C to move in unison with the arm D. When the opening movement has proceeded to the extent of approximately 25 40 70 degrees, this movement of the arm C under the combined pull of the arms E, E' and the link H, causes the butt end c' of the arm C to bind against the inner face of the plate B to a sufficient extent to oppose a slight 45 resistance to the further opening of the door, the stiffness in the action of the hinge thus minimizing the risk of damage occurring by hasty opening of the door. In the fully 50 open position the butt ends e² of the arms E, E' lie snugly against the body hinge plate at each side of the spur G. Conversely, near the beginning of the closing movement, the link H pushing the arm C causes the butt end c' to bind against the inner face of the 55 plate B and tends to prevent slamming of the door.

What I claim and desire to secure by Letters Patent of the United States is:—

1. In a hinge of the kind set forth, having 60 a body hinge plate, two arms pivoted to said body hinge plate, one of said arms comprising a cam surface, a door hinge plate, an arm on said door hinge plate pivottally connected at different parts of its length with both said 65 arms on said body hinge plate, and a spur

on said door hinge plate adapted to work in contact with said cam surface, the combination therewith of means to hold said spur in contact with said cam surface during both the opening and closing movements. 70

2. In a hinge of the kind set forth having a body hinge plate, two arms pivoted to said body hinge plate, a door hinge plate, an arm on said door hinge plate pivottally connected at different parts of its length with both said arms on said body hinge plate, and a spur on said door hinge plate adapted to engage one of the said arms on said body hinge plate, the combination therewith of a link pivottally connected with said spur and also pivottally connected with an intermediate part of the pivoted arm on said body hinge plate remote from said spur. 75 80

3. In a hinge of the kind set forth having a body hinge plate, two arms pivoted to said body hinge plate, one of said arms comprising a cam surface, a door hinge plate, an arm on said door hinge plate pivottally connected at different parts of its length with both said arms on said body hinge plate, and a spur on said door hinge plate adapted to engage the said cam surface, the combination therewith of a link pivottally connected with said spur and also pivottally connected with an intermediate part of the pivoted arm on said body hinge plate remote from said spur to hold said spur in contact with said cam surface during both opening and closing movements. 90 95

4. In a hinge of the kind set forth having a body hinge plate, a door hinge plate, a plurality of arms pivoted to said body hinge plate, an arm on said door hinge plate pivottally connected at different parts of its length with the outer end of each of said arms on the body hinge plate, and a spur on said door hinge plate adapted to engage one of said arms on said body hinge plate, the combination therewith of a link connecting said spur with an intermediate part of the arm on the body hinge plate remote from said spur, said link and its connections being adapted to co-operate with said arm on the door hinge plate to cause stiffness at certain points in the opening and closing movements. 100 105 110 115

5. In a hinge of the kind set forth, having a body hinge plate, a door hinge plate, a plurality of arms pivoted on said body hinge plate, a plurality of arms on said door hinge plate connected by a pivot pin with one of said arms on said body hinge plate, and a spur on the door hinge plate adapted to engage the last named arm, the combination therewith of a link pivottally connected with said spur and with one of said arms on said body hinge plate and adapted to engage said pivot pin at the fully open position to act as a stop to prevent further opening. 120 125
